SQUEEGEE

Filed Dec. 17, 1938

Inventor

James P. Lynch

UNITED STATES PATENT OFFICE

117,402

DESIGN FOR A SQUEEGEE

Jeremiah P. Lynch, Oak Park, Ill., assignor to General Outdoor Advertising Co., Chicago, Ill.,
a corporation of New Jersey

Application December 17, 1938, Serial No. 81,853

Term of patent 7 years

To all whom it may concern:

Be it known that I, Jeremiah P. Lynch, a citizen of the United States, residing at 823 South East Avenue, Oak Park, in the county of Cook and State of Illinois, have invented a new, original, and ornamental Design for a Squeegee, of which the following is a specification, reference being had to the accompanying drawing, forming part thereof.

Fig. 1 is a plan view of the squeegee showing my new design;

Fig. 2 is a side view thereof;

Fig. 3 is a bottom plan view thereof.

I claim:

The ornamental design for a squeegee, substantially as shown.

JEREMIAH P. LYNCH.
